UNITED STATES PATENT OFFICE.

OLIVE E. CONANT, OF LAWRENCE, MICHIGAN.

SAD-IRON HOLDER.

1,203,310.

Specification of Letters Patent. Patented Oct. 31, 1916.

Application filed August 12, 1916. Serial No. 114,585.

To all whom it may concern:

Be it known that I, OLIVE E. CONANT, a citizen of the United States, residing at Lawrence, in the county of Van Buren and State of Michigan, have invented certain new and useful Improvements in Sad-Iron Holders, of which the following is a specification.

This invention has reference to sad iron holders, and as its primary aim and object 10 contemplates the provision of a device of this character that can be readily attached to an ironing board or other suitable main support for maintaining a hot iron in a convenient 15 position within easy reach of the operator.

An equally important object of the invention resides in the provision of an iron support and guard formed from a single piece 20 of wire so connected to the frame of the holder that the portions forming the guard will brace each other and thereby increase the rigidity and effectiveness of the device.

Among the other aims and objects of the 25 invention may be recited the provision of a device of the character mentioned with a view of compactness, and in which the number of parts are few, the construction simple, the cost of production small, and the efficiency 30 high.

Other and further improvements and novel details in the construction and arrangement of parts will be apparent from the description to follow which for a clear 35 understanding of the invention should be considered in connection with the accompanying drawings forming a part hereof wherein the preferred embodiment of the invention is shown for the purpose of illustration.

In the drawings: Figure 1 is a top plan of my invention connected to the ironing board. Fig. 2 is a side elevation of the same.

Referring more particularly to the drawings in which similar reference numerals 45 designate like and corresponding parts throughout the several views, I have illustrated an ironing board 1 in one end of 50 which are provided spaced openings 2 for removably receiving my improved sad iron holder.

In the present instance the holder consists of a substantially U-shaped frame including an intermediate portion 3 and spaced parallel arms 4 and 5 which terminate in

right angularly extending feet 6, removably anchored in the openings 2, the arms being adapted to rest on a portion of the board 1 as illustrated in the drawings. This frame 60 may be and preferably is formed from a single piece of substantially stiff yet resilient wire.

In supporting an iron on the frame I have provided my improved supporting and 65 guarding means which may be and preferably are formed from a single piece of wire. The wire is coiled as illustrated by the numeral 7 about the arm 4 and extended across the frame to provide a transverse rib 8 being 70 coiled as indicated by the numeral 9 on the other arm 5. The piece of wire continuing from the coil 9 bent in a semi-circular formation to provide a guarding element 10 being again coiled about the arm 5 as illustrated by the numeral 11 and then extending in a reverse direction to provide a transverse rib 11 arranged in parallel spaced relation with the rib 8 and engaged on the arm 4. The wire is extended and connected in this 80 manner to provide a plurality of transverse ribs 8 and 11 and also to provide guarding elements arranged adjacent the arms and the intermediate portion 3. It will be noted upon reference to Fig. 2 that the guarding 85 element 12 is similar in construction to the guarding element 11 and continued from the rib 8 braces the adjacent rib 13. All of the ribs brace each other throughout that portion of the frame where they are connected. 90 After the transverse ribs are provided the wire is extended to provide longitudinal ribs 14, said ribs being coiled at uniformly spaced intervals throughout their length and engaged about the transverse ribs as indicated by the numeral 15. The longitudinal rib 14 adjacent the arm 4 is extended to engage the arm 4 and is finally anchored as indicated by the numeral 16 on the frame. After a plurality of longitudinal ribs are 95 provided the opposite end of the wire is anchored as at 17 on the frame. As is apparent, the ribs are arranged in spaced parallel relation with the ribs 15 so that in effect a substantially large mesh support is provided and since the wire is formed of substantially resilient material a somewhat yieldable support for the iron is provided 100 while the guarding elements 10, 13, and 14 brace each other and prevent the accidental slipping of the iron over the edge of the frame.

100

105

110

It is to be noted that because of the resiliency of the material from which the device is formed when the feet 6 are anchored in the openings and the free ends 5 of the arms 4 and 5 partially supported on the board 1, the weight of the iron on the supporting means will have a tendency to increase the efficiency of the engagement of the feet and prevent accidental displacement 10 of the device from the board. Incidentally the feet can be easily inserted and withdrawn from the openings. Furthermore, it is thought from the foregoing that the detailed description of the operation of the 15 invention is unnecessary.

While I have shown and described the preferred form of my invention, I desire it to be understood that I am not to be limited to the particular formation of the arm 20 ranged wire on the support it being essential however that a support is provided and that the guarding elements are formed so as to brace each other and thereby increase the rigidity of the device.

25 As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. It is also to be understood that the language used in the following 30 35 claims intended to cover all of the generic and specific features of the invention herein described and all statements of the scope of the invention, which, as a matter of language, might be said to fall therebetween.

40 Having thus fully described my invention, what I claim as new and desire to secure by Letters Patent, is:

1. A sad iron holder including a supporting frame adapted to be connected to an 45 ironing board, an iron support formed from a single piece of wire connected to the frame to provide a substantially meshed structure.

Copies of this patent may be obtained for five cents each, by addressing the "Commissioner of Patents, Washington, D.C."

2. A sad iron holder including a substantially U-shaped frame adapted to be connected to a suitable support, an iron support formed from a single piece of material connected to the frame and arranged to form a meshed structure, and guarding elements formed from the same piece of wire and arranged adjacent the edges of the frame to prevent accidental displacement of an iron therefrom. 50 55

3. A sad iron holder including a substantially U-shaped frame adapted to be extended from a suitable support, and a single piece of wire connected to the frame and arranged to provide an iron support and a guard for preventing displacement of an iron from the support. 60 65

4. A sad iron holder including a substantially U-shaped frame having feet on the inner end thereof adapted to be removably connected in a suitable support and maintain the frame in a laterally extended position, and an iron support formed from a single piece of wire connected to the frame and arranged to provide a substantially meshed structure. 70

5. A sad iron holder including in combination with an ironing board having spaced openings therein, of a U-shaped frame, feet extending from the inner ends of the frame and anchored in the openings so as to support the frame in a laterally extended position with respect to the board, and an iron support formed from a single piece of material connected to the frame and arranged to form a meshed structure, guarding elements formed from the same piece of wire 75 80 85 and arranged adjacent the edges of the frame to prevent accidental displacement of an iron therefrom, and each of the guarding elements bracing each other for increasing the rigidity and effectiveness of the device. 90

In testimony whereof I affix my signature in presence of two witnesses.

OLIVE E. CONANT.
